UNITED STATES PATENT OFFICE.

FRANZ NEUBER, OF VIENNA-NEUSTADT, AND JOSEPH TAMBOUR AND CARL COLBERT, OF VIENNA, AUSTRIA-HUNGARY.

SAFETY LOCKING DEVICE FOR FIREARMS.

SPECIFICATION forming part of Letters Patent No. 678,420, dated July 16, 1901.

Application filed May 18, 1900. Serial No. 17,111. (No model.)

To all whom it may concern:

Be it known that we, FRANZ NEUBER, a resident of Vienna-Neustadt, and JOSEPH TAMBOUR and CARL COLBERT, residents of Vienna, 5 in the Empire of Austria-Hungary, subjects of the Emperor of Austria-Hungary, have invented a new and useful Improvement in Safety Locking Devices for Triggers of Firearms, of which the following is a specification.

The object of the present invention is a safety locking device for triggers of firearms, the chief characteristic of which is that the trigger is both prevented from being pulled 15 backward and also insured against lateral movement resulting, as is frequently the case, from impact or shock or the like, while the device is unlocked by simply gripping the small of the stock in any firing position independently of the placing it against the shoulder. The means by which these results are obtained may be various, but consist in principle thereof that a locking and unlocking device lying in a groove in the small of the 20 stock grips the trigger by means of a fork or of a projection engaging in a groove in the trigger, and vice versa, or that the said locking and unlocking device holds the trigger for its whole breadth.

30 In the accompanying drawings, in which similar letters of reference refer throughout to similar parts, Figure 1 is a side view of the safety device locked, the locking and unlocking device in this case consisting of a lever of the first class. Fig. 2 is a view of the same, but in an unlocked position, being in the position it assumes after the firearm has been discharged. Fig. 2^a is a section on the line 2 2 of Fig. 2, looking down, with parts 35 removed. Fig. 3 represents the safety device locked, the locking and unlocking device consisting in this case of a lever of the second class. Fig. 3^a is a top plan of the lever seen in Fig. 3, with the projection in section. Fig. 4 is a side view of the safety device 40 locked, the locking and unlocking device consisting of a bar which is pressed in a substantially straight line in guides. Fig. 4^a is an elevation of the lever seen in Fig. 4. Fig. 4^b is a plan thereof. Figs. 5, 6, and 7 represent in section various forms of construction

of that part of the locking and unlocking device which engages the trigger. Figs. 8, 9, and 10 represent in various forms of construction the bow or guard which protects separately the trigger and the locking and unlocking device. The other figures represent details of the various forms of construction of the device.

In the first form of construction the safety device 60 consists of a lever *b* of the first class capable of turning on the pivot *a*. The front portion of said lever *b* is normally pressed upward by a spring *d* in such a manner that the rear portion of the lever, which passes 65 through the trigger-plate of the firearm, projects from the bottom of the small of the stock. The front part of the lever *b* is forked, as shown in Fig. 2^a, and within said fork is a step-shaped cross-piece *c*. In the resting position the said cross-piece *c* is behind a projection *f* on the trigger, and the latter is thereby locked in such a manner that the trigger cannot move either backward or sidewise, Fig. 1. When, however, the firearm is gripped by 75 the small of the stock—*i. e.*, in the manner it is held when being discharged—the lever *b* is pressed into the stock, and the cross-piece *c* is thus moved from the projection *f* on the trigger to a position below the said projection. Consequently the trigger is free and the firearm can be discharged. When the pressure on the lever *b* ceases, the firearm is locked again automatically by the upward movement of the front part of the lever by means of spring *d*, 80 as described. In order that in returning to the locking position no jamming should occur between the trigger and the lever *b*, the trigger is provided with a pin *g*. In the position of the trigger when the firearm has been discharged the said pin *g* is above the fork, (see Fig. 2,) and consequently the lever *b* is prevented from returning to its normal position until the trigger has been moved forward by the action of the spring *j*—that is to say, 85 until the trigger has returned to its normal position. The same result can be obtained by means of a lever of the second class or by means of a bar moving in straight guides, as is shown in the two following forms of construction. In the first thereof the locking device (see Figs. 3 and 3^a) consists of a lever

of the second class moving in a recess *h* in the small of the stock and pivoted at one end at *a*. A spring *d* acts upon the lever *b* at about the center thereof, and said lever passes through the trigger-plate in such a manner that it projects from the bottom of the small of the stock. The other end of the lever *b* is bent in two places and has the same shape as the lever in the first form of construction, as shown in Fig. 3^a, with the exception that the cross-piece *c* in the fork is reversed. The second of these forms of construction, Figs. 4, 4^a, and 4^b, is preferably employed in firearms in which the small of the stock is very narrow and there is not enough space for the lever *b* to move on its pivot *a*. In this form of construction no lever is used, but in place thereof a bar *b*, moving in straight guides. In this instance the guides consist of two plates *i*, fixed to the said bar and provided with slots *k*, in which the pins *l*, fixed to the stock, slide, and vice versa. The spring device in this form of construction consists, preferably, of the two similar springs *d*. In the two latter forms of construction the lever or bar *b* is also pressed into a groove in the stock when the small of the stock is gripped, so that the cross-piece *c* is moved above the projection *f* and the trigger thus becomes free and the firearm can be discharged.

After the discharge of the firearm the cross-piece *c* remains above the projection *f* until the trigger has been moved forward by the action of the spring *j*. Simultaneously with said forward movement of the trigger the lever *b* is moved back to the locking position by the pressure of the spring *d*, so that the device is immediately locked again.

It will be seen that in the forms of construction shown in Figs. 5, 6, and 7 no fork is provided. In these forms the supporting of the trigger by the locking and unlocking device is effected by means of a projection fixed either to the trigger or to the said device and moving in a slot, or the locking and unlocking device lies flat against the whole breadth of the trigger. In the former form of construction, Fig. 5, the front part of the locking and unlocking device *b* is provided with a projection which runs in a groove in the trigger. In the second form of construction, Fig. 6, the arrangement of the projection and the groove is reversed, the said projection being fixed to the trigger and the groove being in the locking and unlocking device. In the third of these forms of construction the locking and unlocking device does not hook onto or grip the trigger, but supports the latter along the whole breadth thereof. In all these forms of construction the advantages possessed by the forked locking and unlocking devices are retained, the trigger being, when the device is locked, protected against backward pull and lateral displacement. In the first two of these forms of construction the locking and the support of the trigger are effected by means of the projec-

tion and groove, while in the last form of construction described the same effect is obtained, the locking and unlocking device being at the front at least equally as broad as the trigger, so that in case lateral pressure is brought to bear on the trigger the latter can never be moved out of the range of the locking and unlocking device.

In order to prevent unintentional or accidental operation of the locking and unlocking device, the same is protected by a bow. This bow can be either separate or connected with the trigger-guard. If the trigger and the locking and unlocking device are protected by a common guard, they are divided by a partition in order to prevent pressure in the direction in which the trigger acts, simultaneously operating the locking and unlocking device and causing the unintentional discharge of the firearm.

In Fig. 8 a guard *e*, surrounding both the trigger and the locking and unlocking device, is represented, in which a fixed partition separates the two said parts. This is also the case in the form of construction represented in Figs. 1 to 4.

Figs. 9 and 10 represent a firearm of the same kind as shown in Figs. 1 to 4, the trigger of which was already provided with the usual guard. A separate guard *q* has been consequently provided for the locking and unlocking device. This separate bow or guard *q* can either, as seen in Fig. 9, be independent of the trigger-guard *p* or can be joined to the latter, as seen in Fig. 10.

Having now described our invention, what we claim as new, and desire to protect by Letters Patent, is—

1. The combination of a pivoted lever, a cross-piece on the forward end thereof, a trigger disposed to be engaged by said cross-piece to prevent both lateral and longitudinal displacement of the same, means movable with the trigger to engage the cross-piece at a predetermined time, and means for retaining said lever in a predetermined position, as set forth.

2. A new and useful safety locking device for firearm-triggers having a pivoted lever a cross-piece on the forward end of the same a trigger adapted to be engaged by said cross-piece in a manner for preventing lateral as well as longitudinal displacement of the same a pin on said trigger adapted to engage said cross-piece at a predetermined time and springs for retaining the said lever in a predetermined position substantially as described.

In testimony whereof we have hereunto set our hands in the presence of witnesses.
